UNITED STATES PATENT OFFICE.

GEORGE E. SHARPE, OF STEUBENVILLE, OHIO.

ELECTRIC HEATER.

1,064,258.

Specification of Letters Patent. Patented June 10, 1913.

Application filed October 30, 1912. Serial No. 728,615.

To all whom it may concern:

Be it known that I, GEORGE E. SHARPE, citizen of the United States, residing at Steubenville, in the county of Jefferson and State of Ohio, have invented certain new and useful Improvements in Electric Heaters, of which the following is a specification.

This invention has for its object the provision of a portable heater especially adapted to use electric lamps as the heating agent and which may be manufactured economically.

The invention also seeks to provide a heater which will be stable when in use, and in which heating will be effected by circulation as well as by radiation.

The invention also seeks to improve, generally, the construction and arrangement of the parts of a heater to the end that the efficiency and durability of the same may be increased, all of which will fully appear from the description hereinafter given.

The invention consists in certain novel features which will be particularly pointed out in the claims following the description.

The invention is illustrated in the accompanying drawings, in which:

Figure 1 is a perspective view of a heater embodying my present improvements; Fig. 2 is a vertical section through the heater extending from front to the rear thereof; Fig. 3 is a rear elevation of the lower portion of the heater; Fig. 4 is a horizontal section taken on the line 4—4 of Fig. 2; Fig. 5 is a detail perspective view of the lower portion of the heater; Fig. 6 is a detail perspective view of a brace employed to reinforce the upper end of the reflector.

In the particular embodiment of the invention illustrated, the main frame comprises side members or pilasters 1 and a crown or head 2 extending between the said side members or pilasters, the said members being preferably channeled castings. The head or crown 2 is shown provided with panels 3 which may be of any desired ornamentation. The head or cross bar 2 is constructed at its lower edge with an inwardly and downwardly extending rabbet, shoulder or flange 4 which receives the upper edge of a slotted bar or grille 5, said bar or grille being secured to the head bolt 6 inserted through its upper edge and the flange 4 of the head and being secured at its ends by bolts 7 passed through offsets 8 of the pilas-

ters 1. The lower edge of this grille or slotted bar is extended inwardly and downwardly to provide an overhanging shoulder, rabbet or flange 9 which fits over the upper edge of a hood or crown 10 which is preferably cast integral with the pilasters and extends between the same. This exact arrangement of these parts, however, is not essential and the details of the same may be varied at will. Between the lower ends of the pilasters 1 is a slotted bar or grille 11 which constitutes a base for the heater and may be secured to the pilasters in any desired or convenient manner. A transverse supporting bar or shelf 12 is disposed in rear of the pilasters and the upper portion of the grille or base 11, and this cross bar or shelf 12 is formed integral with the legs 13 which fit against the rear faces of the pilasters between the flanges thereof and are rigidly secured thereto by bolts 14, the ends of the shelf being upturned, as shown at 14^a. Secured to the rear face of the head or cross bar 2 is the flange 15 at the upper end of a drum or casing 16 which extends rearwardly and downwardly from the said head and then extends downwardly parallel with the front plate or main frame, the drum or casing having its lower end in the same horizontal plane as the lower ends of the pilasters and the lower edge of the base or grille 11. The side walls 16^a of the drum or casing extend to and are secured to the pilasters so that a heating space between the drum and the front frame is provided, the edges of said side walls being extended laterally above the legs 13, as shown at 16^b. The lower edge of the drum provides an extended supporting base for the heater so that, when the same is set up for use, it will be steady and will not easily topple over.

A reflector 17, preferably of highly burnished sheet copper, is provided between the drum and the front frame and is preferably shaped to provide a number of cells 18, each adapted to fit around an electric lamp bulb, as illustrated most clearly in Figs. 1 and 4. The upper end of the reflector is open, as shown clearly in Fig. 2, and the back of the reflector is in spaced relation to the back of the drum or casing. The lower end of the reflector is covered by a bottom plate 19 which extends to the upper edge of the base or grille 11 and is reinforced by a supplemental plate 20 rigidly secured to the lower end of the back wall of the reflector and ex-

tending across the drum and bearing against the side walls thereof, as shown most clearly in Fig. 4, so that the reflector will be reinforced and will not tend to lose its shape. 5 Buckling of the drum is also prevented by the employment of this reinforcing or supplemental bottom plate. The front edges of the bottom 19 and the supplemental or reinforcing plate 20 are bent downward, as at 10 20^a, and secured to the inner face of the grille 11 at the upper edge thereof, the ends of the plate 19 being extended over the upturned ends 14^a of the shelf 12, as shown at 15 20^b. To still further reinforce the reflectors and maintain the shape of the same, I provide the supports or spacing plates 21 which are secured rigidly to the back wall of the drum and extend forwardly therefrom to engage between the convolutions of the reflector, as shown clearly in Fig. 4, to thereby prevent collapse of the reflector. A brace 22 is also provided at the upper end of the reflector, said brace consisting of a flat bar rigidly secured to the upper end of each cell 20 25 of the reflector and having its ends turned rearwardly, as shown at 23, to be secured to the side walls of the drum.

The sockets 24 are secured upon the shelf 12 by screws or bolts 25 inserted through the 30 bases of the sockets and the said shelf or in any other convenient manner and they are connected by conductors 26, as will be readily understood. These sockets may be of any ordinary standard type and the details of the same are not illustrated as they form no part of my present invention. The electric lamp bulbs 27 are inserted through openings provided therefor in the bottom plate 19 and the reinforcing plate 20 and engage the sockets in the usual manner, the 35 openings through which the stems of the bulbs pass and the sockets being so disposed that the bulbs will occupy a concentric relation to the cells of the reflector. A switch 40 45 28, or controlling buttons, may be placed at any convenient point to permit the current to be turned on or cut off, the central point of the lower grille being generally preferred.

When the current has been turned into the 50 lamps, the heat generated by the same will be thrown outwardly by the reflector and at the same time air will pass into the openings of the lower grille or base 11 and flow under the bottom plates of the reflector and 55 then upwardly between the reflector and the drum or casing, finally escaping through the openings of the upper grille or across the open upper end of the reflector and under the hood if the grille be not employed. 60 I thus effect heating by radiation as well as by circulation so that the temperature of the room is quickly raised to the desired degree. The drum and the reflector are preferably constructed of sheet metal so that the 65 heat will be readily given off and buckling

of these parts is effectually prevented by the bar 22, the spacing plates 21 and the reinforcing bottom plate 20, as will be readily understood. The lamps and their sockets will be effectively supported by the shelf 12 70 so that disarrangement or damage to the conductors will be prevented, inasmuch as the frame, drum and the bottom 19 of the reflector entirely inclose the shelf and the sockets. Should a lamp be burnt out or 75 otherwise become useless, it may be readily withdrawn from the socket, the open upper end of the reflector permitting sufficient longitudinal movement of the lamp for it to be disengaged from the socket, and the opening above the lower grille 11 and between the same and the crown or hood 10 being ample for the withdrawal of the lamp. The device is very simple in its construction and the arrangement of its parts and may be 80 easily moved from point to point so that it may be set up and used at the place in a room where it will be most apt to produce the desired results.

It will be readily noted that the several 90 securing bolts are accessible so that the face plate or main frame may be removed from the drum, the reflector and the supporting shelf, without necessitating a disconnection of the reflector from the drum or a separation of the reflector and the shelf. The drum may also be removed from the face plate and the reflector without requiring the reflector to be separated from the face plate or from the shelf so that a damaged part 95 may be replaced without necessitating the provision of an entirely new heater and the substitution of a new part for any part which is still useful. It will also be noted that, while the device is portable and may 100 be placed anywhere in a room, it may be set into a fire-place so as to completely fill the same and impart an ornamental finish to the opening. The spacers and the bar 22 effectually prevent such buckling of the reflector as will obstruct the passage between the reflector and the drum and hold the upper end of the reflector in proper spaced 105 relation to the drum and the face plate. Moreover, the spacers create a plurality of 110 flues between the reflector and the drum so that the air entering the lower grille of the face plate will be caused to rise positively through the space between the drum and the reflector and the creation of laterally flowing currents will be avoided.

What I claim is:—

1. The combination of a main frame having a central opening therethrough, a shelf disposed below the said opening and secured to the frame at the sides of the opening, a reflector having a bottom plate resting upon the ends of the shelf and supported thereby in spaced relation to the shelf, and a heating member secured upon the said shelf and pro- 125 130

jecting upwardly through said bottom plate in front of the reflector.

2. The combination of a main frame having a central opening therethrough and having upright side members, a reflector fitted to the frame and disposed in rear of the said opening, a support for the lower end of the reflector detachably secured to the main frame, and a drum inclosing the reflector and spaced from the same throughout its extent, said drum having its upper end secured to the rear face of the frame at the upper end thereof and its side walls bearing against the side members of the frame and provided with lateral extensions secured to said side members above the said support.

3. The combination of a main frame having a central opening therethrough, a shelf arranged in rear of the main frame and below the said central opening and provided with up-turned ends, legs rigid with said up-turned ends and secured to the rear side of the main frame, a reflector having a bottom plate extending between the ends of the shelf, a reinforcing plate secured to the bottom of the reflector and extending between and fitting over the up-turned ends of the shelf, and a heating member supported by the shelf and projecting upwardly through the bottom of the reflector and in front of the main portion of the same.

4. The combination of a frame having an opening therethrough and having upright side members, a shelf arranged in rear of the frame below the opening through the same, said shelf having upturned ends and provided at the front edges of its ends with legs bearing against the rear face of the side

members of the frame and secured thereto, and a reflector in rear of and spaced from the frame and having a bottom plate resting on and fitting over the up-turned ends of the shelf, the front edges of the reflector and said bottom plate bearing against the rear face of the frame at the sides of and below the opening through the same.

5. The combination of a frame having an opening therethrough and having upright side members, a shelf arranged in rear of the frame below the opening through the same, said shelf having upturned ends and provided at the front edges of its ends with legs bearing against the rear faces of the side members of the frame and secured thereto, a reflector in rear of and spaced from the frame and having a bottom plate resting on and fitting over the upturned ends of the shelf, the front edges of the reflector and said bottom plate bearing against the rear face of the frame at the sides of and below the opening through the same, and a drum inclosing the reflector and spaced from the same throughout its extent, said drum having its upper end secured to the rear face of the frame at the upper end thereof and its side walls bearing against the side members of the frame and provided with lateral extensions secured to said side members above the said legs.

In testimony whereof I affix my signature 70 in presence of two witnesses.
